UNITED STATES PATENT OFFICE.

MARIE B. DUFFY, OF TOLEDO, OHIO.

WINDOW GUARD.

Application filed August 7, 1922. Serial No. 580,109.

To all whom it may concern:

Be it known that I, MARIE B. DUFFY, a citizen of the United States, and a resident of Toledo, in the county of Lucas and State of Ohio, have made an invention appertaining to a Window Guard; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention has for its object to provide an efficient, substantially burglar-proof guard for an open window. The invention provides a means for locking a window in an open position, and also a grating that cannot be readily opened from without, which effectually closes the space left open by the window sash. It is so constructed that it cannot be readily "jimmied" and so that it may be readily applied and opened and closed. It also provides means whereby it may be either folded into the window frame or swung to one side on the window casing.

The invention may be contained in structures which in their details may be varied. To illustrate a practical application of the invention I have selected a window guard containing my invention as an example of structures containing the invention and shall describe it hereinafter. The structure selected is illustrated in the accompanying drawings.

Figure 1 of the drawings illustrates the guard that is pivotally secured to the window frame. Fig. 2 illustrates a part of the guard folded and swung to one side. Fig. 3 illustrates a simple locking device that may be used for locking the guard. Fig. 4 illustrates a locking bracket secured to the window sill. Fig. 5 illustrates a portion of the guard in position when located within the window casing. Fig. 6 illustrates a modified form of structure having foldable parts. Fig. 7 illustrates a portion of the window guard of Fig. 6 in position when the window is open. Fig. 8 illustrates a sectional view taken on the line 8-8 indicated in Fig. 6.

In Figs. 1 and 6, 1 is the window frame. 2 is the lower window sash that is slidably raisable in the frame 1 in the manner well

known. The guard 3 in the form of the invention illustrated in Figs. 1, 2 and 3 comprises a pair of lazy tongs 4 formed of metal strips of suitable width and thickness to effectually protect the opening produced when the sash 2 is raised a short distance in the frame 1. The lazy tongs are provided with suitable members for interconnecting them and also for connecting them to the window frame. They are provided with the comparatively wide strips 5 to which the inner ends of the lazy tongs are connected, one or more of the adjoining strips of each of the lazy tongs being pivoted to a strip 5 and one or more of the adjoining strips being connected to a strip 5 by means of a pin and slot connection 6. Also each of the lazy tongs is connected to a strip 7, one or more of the adjoining strips of the lazy tongs being pivoted to the strip 7, and one or more of the adjoining strips being connected to the strip 7 by a pin and slot connection 8. The strips 7 are hingedly connected to the strips 9 and the strips 9 are secured to the window frame. Thus the strips 5 and the lazy tongs 4 may be pushed back to the frame and swung on the pivots 10 to one side of the window frame.

In order to secure the guard to the sill a U bracket 11 is secured to the window sill. The U bracket 11 is provided with slots 12 that extend from the edges of the bent portion of the U bracket, leaving between the ends of the slots a tongue 13 that is integral with the sides of the bracket. The strips 5 are provided with slots 14 that fit the tongue 13. When the strips 5 are placed contiguous the slots 14 are fitted to the tongue 13 and the lower ends of the strips 5 fit in the slots 12. This prevents the guard from being raised and also from being pushed inward or pulled outward, and thus the lower ends of the strips are held in position. The upper end of the strips 5, and consequently the upper edge of the central portion of the guard is held in a similar manner, as by the strips 15 that are secured to the strips 5 and the bracket 16. The strips 15 are bent angularly inward so as to place the upper edge of the guard substantially within the plane of the window sash 2 and yet afford a connection between the strips 15 and the bracket 16. The bracket 16 is also provided with slots and a tongue which fits the slots 17 formed in the ends of the strips 15. This prevents the

upper edge of the guard from being pushed inward or pulled outward and also prevents the strips 5 from being wedged to the right or to the left when the strips 5 are locked 5 together.

The strips 5 may be locked by any suitable means, such as by a padlock. I have, however, shown a simple device which is very difficult to operate, except from the inside of 10 the window, for efficiently locking the strips 5 together. The locking means consists of a cylindrical block 18 which is eccentrically pivoted to one of the strips 5 by means of a screw 19. A spring 20 is located intermediate 15 at the head of the screw 19 and the bottom of a socket 21 formed eccentrically in the block 18. The block 18 is provided with a pin 22 that enters a hole 23 formed in the strip 5 other than the one to which the block 20 is pivotally secured. The eccentric relation of the spring 20 to the block 18 renders it exceedingly difficult to move the block 18 so as to raise the pin 22 from the hole 23 when operating from the outside of the window 25 and through the small spaces or cracks formed by the lazy tongs, while from the inside of the window the block 18 may be readily pulled back, pulling in line with the axis of the screw 19 so as to move the pin 22 from the hole 23. When the block 18 has been pulled from the strips 5 it may be easily turned so as to unlock the strips.

When the sash 2 is lowered the position of the bracket 16 is so located on the sash 35 that it will be placed slightly above the bracket 11 and when the window 2 is raised and the strips 5 are placed in locking position the brackets 11 and 16 engaging with the strips 5 and 15 prevent the sash from being raised any higher. Thus the space below the sash is securely guarded when the sash is up.

In the form of the device illustrated in Fig. 5 each of the lazy tongs 4 is connected 45 to the web of a T or L strip 24 and the strip 24 is secured to a studding 25 located within or at the side of the frame 1. The frame 1 is provided with an opening 26 that is formed in line with the sash 2 and of a height sufficient to receive strips 5 and 15 whereby the lazy tong parts may be readily slipped into 50 the casing of the window.

The lazy tongs 4 preferably partake of the form of the lazy tong construction illustrated in Figs. 6, 7 and 8 wherein the parts 55 of the lazy tongs when operated lie close to each other. In order that the window may be opened at a greater width the parallel strips of the lazy tongs are pivotally connected at a plurality of intermediate points. In the form of construction illustrated in 60 Figs. 6 and 7 the strips are connected together at five points, three of the points being intermediate.

65 In order to prevent tampering with the

lock, strips 27 extend from the second lower row of points of connection between the strips to the fourth row of points of connection between the lazy tong strips, which closes the opening between the lazy tong strips that are connected at these points. The upper ends of the strips 27 are slotted while the lower ends have openings about the size of the shanks of the pins that connect the parts of the lazy 70 tong construction together. The strips 27 are secured by the pins of the second and fourth rows. The slots permit free movement or action of the lazy tong construction. The locking means 28 is located substantially 75 in line with the third lower row of points of connection of the lazy tongs and hence the lock is protected from any attempt to open the same.

The lazy tongs in the form of construction illustrated in Fig. 6 are provided with strips 29 and 30 that are hingedly connected together by means of the hinges 31. This divides the lazy tongs into four parts 32 and 33. The parts 32 are secured to the bent 80 strips 34 that are hingedly connected to the strips 35. The strips 35 are secured by any suitable means to the frame 1 on the window. The strips 34 are so bent as to bring the lazy tongs in the plane of the sash notwithstanding the fact that the strips 35 are secured to the inside of the frame as indicated in Fig. 8. The strips 34 are thus bent 85 at an angle so that they will conform to the shape of the frame.

The lazy tong parts 32 are connected to the strips 30, while the lazy tong parts 33 are connected to the strips 29 and to the strips 36. The strips 30 extend beyond the upper and lower edges of the guard and are provided with slots 37 that engage in brackets 38 and 39 similar in construction to the brackets 11 and 16. The strips 36 are similar to the strips 5 and are secured to brackets 40 and 41 that are also similar to the brackets 11 and 16, whereby the guard is secured in position to the window sash and to the sill of the frame when the lazy tong parts are in closed and locked position. When the lazy tongs are folded together by 105 moving the strips of the lazy tongs toward each other and the lazy tong parts are folded by means of the hinges 31 they may be swung to one side of the window by means of the hinges 42.

If desired, the window may be locked in closed position, that is, with the sash down, by placing the guard in locked position, and a strip 43 may be placed over a staple 44 and the locking means 45 secured in the 115 staple. The strip 43 may be pivotally connected to one of the strips 36 and thus may be folded down over the guard when not in use. This provides a convenient means for locking the window when closed.

The construction illustrated in Figs. 6 and 7 may also be secured within the window frame as shown in Fig. 5, it being understood that Fig. 5 illustrates an adaptation 5 of the guards illustrated in Figs. 1 and 6.

I claim:

1. In a window guard, a pair of lazy tong parts hingedly connected to the frame of the window and connected to metal strips, 10 a bracket located on the window sash and a bracket on the window sill having tongues and slots, the strips having slots, the tongues of the brackets fitting the slots of the strips, and the strips fitting the slots of 15 the brackets, means for locking the strips together.
2. In a window guard, a pair of lazy tong parts hingedly connected to the frame of the window and connected to metal strips, 20 a bracket located on the window sash and a bracket on the window sill having tongues and slots, the strips having slots, the tongues of the brackets fitting the slots of the strips, and the strips fitting the slots of the strips, 45

the brackets, means for locking the strips together, parts of the lazy tong parts having strips that extend substantially at right angles to the sill and located in proximity to the first named strips, the locking means being located between sets of the last named 30

3. In a window frame having an opening, a pair of lazy tong parts connected to the window frame at a point within the opening for receiving the lazy tong parts within 35 the frame when the lazy tong parts are folded, metal strips connected to the lazy tong parts, a bracket located on the window sash and a bracket on the window sill having tongues and slots, the strips having slots, 40 the tongues of the brackets fitting the slots of the strips, and the strips fitting the slots of the brackets, means for locking the strips together to lock the lazy tong parts when open.

In testimony whereof, I have hereunto signed my name to this specification.

MARIE B. DUFFY.
